WALL TILE

Philip E. Kopp, Minerva, Ohio

Application February 4, 1958, Serial No. 49,496

Term of patent 14 years

(Cl. D18—2)

The figure is a perspective view of the wall tile, showing my new design.

The back and bottom of the wall tile are mirror images of the front and top.

I claim:

The ornamental design for a wall tile, as shown and described.
